GEORGE BURKET AND SAMUEL M. GASKILL, OF BLUFFTON, OHIO.

Letters Patent No. 63,009, dated March 19, 1867.

IMPROVEMENT IN HEAD-BLOCKS FOR SAW-MILLS.

The Schedule referred to in these Letters Patent and making part of the same.

TO ALL WHOM IT MAY CONCERN:

Be it known that we, GEORGE BURKET and SAMUEL M. GASKILL, of Bluffton, in the county of Allen, and State of Ohio, have invented a new and improved Head-Block for Saw-Mills; and we do hereby declare that the following is a full, clear, and exact description thereof, which will enable those skilled in the art to make and use the same, reference being had to the accompanying drawings forming part of this specification, in which—

Figure 1 is a side view of our invention.

Figure 2, a plan or top view of the same.

Figure 3, a transverse vertical section of the same, taken in the line $x\ x$, fig. 2.

Figure 4, a horizontal section of the same, taken in the line $y\ y$, fig. 1.

Figure 5, a detached plan or top view of a portion pertaining to the same.

Figure 6, an inverted plan of a knee or stand, and pertaining to the same.

Figure 7, a detached view of a portion of a shaft pertaining to the same, with weighted or loaded lever attached; and

Figure 8, a section of the same, taken in the line $z\ z$.

Similar letters of reference indicate corresponding parts.

This invention relates to a new and improved head-block for saw-mills, and it consists in an improved mechanism for setting the log to the saw, and also in an improved reversing mechanism for gigging back the carriage, as hereinafter fully shown and described.

A represent the ways or guides on which the carriage B works, the latter being operated by a pinion gearing into a rack underneath the carriage as usual, and the pinion-shaft, having two pulleys upon it, over one of which a straight belt is fitted, and a cross-belt over the other; an idle or loose pulley is also placed on this shaft to receive the belt which is not in use. This arrangement is precisely the same as that now used for operating the carriage.

Our improvement relates to a mode of operating or shifting the belts to give the feed and reversing or gigging-back movement to the carriage as hereinafter shown and described.

C represents a block, which is keyed, or otherwise secured, transversely on the carriage B, and having a horizontal plate, a , fitted in grooves in its upper part so that it may slide freely back and forth therein.

This plate a has a knee or standard, D, on its upper surface, against which the log E to be sawed abuts, and is secured to it by dogs in the usual way, the log resting on the block C, as shown in fig. 3.

The under side of the plate a has a cavity in it containing a series of pawls which rest upon a rack, F, placed longitudinally in the block C, and so arranged that it may slide therein, or have a reciprocating motion imparted to it; said pawls being independent of each other, but capable of all being raised simultaneously from the rack by having a bit or projection, e, on the shaft d on which the pawls are fitted, said bit or projection fitting in a recess in the pawls, as shown in fig. 3, and the shaft d provided with a lever, F $\times$, for the convenience of turning it.

The rack F, in connection with the pawls b, sets the log to the saw, the rack, when moved in the direction indicated by the arrow 1, moving the knee or standard D in consequence of the teeth of the rack acting against the pawls b. When the rack is moved in the opposite direction, as indicated by arrow 2, the teeth of the rack slip past the pawls, and the knee or standard is not moved. This will be fully understood by referring to fig. 3.

The pawls b are of different lengths, as shown in fig. 6, so as not to admit of any useless play or movement of the rack F. Four of these pawls may be used, but we do not confine ourselves to any particular number.

The rack F is operated as follows.

G is a bar which is fitted on arms e e attached to one side of the carriage B, and allowed to slide freely thereon. This bar works through the block C, and has bevelled bars H H' attached to each side of it by clamps, I, so arranged that the bars H H' may be adjusted nearer together or further apart, as may be desired. The bars H H' may act against friction-rollers in the block C, the bar H moving the rack F, and consequently the knee or standard D, in the direction indicated by arrow 1; the bar H' moving it in the opposite direction, as indicated by arrow 2. (See figs. 2 and 3.)

By this arrangement it will be seen that the knee or standard is moved forward, and the log set to the saw, until the former reaches the end of the block C, when the pawls *b* are raised free from the rack by turning the shaft *d*, and the knee or standard moved back to its original position, and another log placed on the block C.

The keys *f* of the clamps I have their thin edges towards the block C, so that in case the bar G be moved too far the keys will come in contact with block C and be knocked out, thereby loosening the clamps and preventing any injury to any of the working parts.

On the bar G there are also two pendent bars, J J', secured in position by keys *g*. The bars J J' are secured at a distance apart equal to the length of the log.

To the flooring of the mill there is secured a stop, K, so arranged that it may be raised and lowered, that is to say, turned upward to a vertical position, or turned downward in a horizontal one. When this stop is raised, and the carriage gigged back, the bar J will come in contact with it and avert the motion of the bar G, and as the block C will move on with the carriage, the bevelled bar H will, towards the close of the gigging-back movement of the carriage, move the knee or standard in the direction indicated by arrow 1, and set the log to the saw, the knee or standard being moved back towards the termination of the feed movement of the carriage by the bar J' coming in contact with the stop K, so as to avert the bar G and admit of the bevelled bar H' acting upon the block C.

The setting of the log for sawing thick or thin lumber is effected by a screw, L, in the end of the rack F, said screw increasing or diminishing the space between the shoulders or pulleys between which the bevelled bars H H' work, as will be fully understood by referring to fig. 3, in which the screw L is shown connected to a movable shoulder or bearing, *h*.

The block C is attached to the carriage by means of a key, *i*, which admits of said block being adjusted to suit any length of log desired.

The reversing of the movement of the carriage B is effected as follows:

M is a shaft placed transversely with the carriage B and ways A A, the shaft running through the latter. This shaft has two levers, N O, attached to it, one, N, being at the outer end of said shaft, and permanently attached to it, with a weight, *i'*, on its end, and the other, O, being allowed a certain degree of free turning movement on the shaft, and having a weight, *i''*, on its end; a pin, *j*, passing through the shaft in connection with lips, *k*, on the hub of the lever, determining the length of the free movement of the lever O. (See figs. 7 and 8.)

This lever O is actuated by adjustable stops, *l l'*, on a bar, P, attached to one side of the carriage B, said stops striking the lever O at the close of each movement of the carriage, and throwing it over so as to turn the shaft and actuate the belt shipper, the weight *i'* being sufficiently heavy to effect that result. The weight *i''* on the lever N is designed to be sufficiently heavy to keep the friction pulley pressed sufficiently hard upon the belt to insure the running of the carriage.

We would remark that we design to have the rack F and bar G supplied with levers, Q Q', so arranged as to admit of said parts being operated by hand when necessary or desired.

Having thus described our invention, what we claim as new, and desire to secure by Letters Patent, is—

The bar G provided with the adjustable bevelled plates H H', secured by clamps I I, substantially as shown, and connected or arranged with the rack F, and also provided with the pendent bars J J'; the above parts being used in connection with the stop K for operating the rack F, substantially as described.

GEORGE BURKET,
SAMUEL M. GASKILL.
